DESIGN FOR A TUBULAR CHAIR

Homer J. Vetter, Seattle, Wash.

Application October 5, 1946, Serial No. 133,786

Term of patent 14 years

(Cl. D15—1)

To all whom it may concern:

Be it known that I, Homer J. Vetter, a citizen of the United States and a resident of Seattle, in the county of King and State of Washington, have invented a new, original, and ornamental Design for a Tubular Chair, of which the following is a specification, reference being had to the accompanying drawing, forming a part thereof.

In said drawing:

Figure 1 is a top plan view showing my new design of a tubular chair.

Figure 2 is a front view thereof; and

Figure 3 is a side elevational view of my said new design.

What I claim is:

The ornamental design for a tubular chair, as shown.

HOMER J. VETTER.
